Wm Wallace White ATTY.

UNITED STATES PATENT OFFICE.

DAVID BAIRD MACDONALD, OF LEICESTER, ENGLAND.

MANUFACTURE OF PICRIC ACID.

1,396,001.

Specification of Letters Patent.

Patented Nov. 1, 1921.

Application filed July 10, 1917. Serial No. 179,775.

(GRANTED UNDER THE PROVISIONS OF THE ACT OF MARCH 3, 1921, 41 STAT. L., 1313.)

To all whom it may concern:

Be it known that I, DAVID BAIRD MACDONALD, a subject of the King of Great Britain, citizen of Leicester, England, residing at Leicester, in the county of Leicester, England, have invented new and useful Improvements in and Relating to the Manufacture of Picric Acid, (for which I have filed applications in England Dec. 15, 1915, Patent No. 17525 of 1915; in England April 15, 1916; in France Dec. 12, 1916; in Russia Jan. 13/26, 1917, and in Italy Dec. 11, 1916,) of which the following is a specification.

This invention relates to the manufacture of picric acid, its object being to enable pure picric acid of a high melting point and free from metallic contamination to be expeditiously and economically produced and without danger.

To this end the invention comprises improvements in known processes of picric acid manufacture and preferably also makes use of an apparatus wherein the process of manufacture may be carried out in an economic manner as will be hereinafter described.

The manufacture of picric acid has been attendant with danger to a greater or lesser extent, but more often than not to a considerable extent, and one of the important results brought about by the present invention is the elimination of danger. Further advantages resulting from the improvements constituting the present invention are a considerable reduction in the time involved, falling temperature during reaction, purity of picric acid produced, and economy of the extracting agents employed.

The principal improvement included in the present invention consists, in the manufacture of picric acid, in separating the picric acid from the metallic impurities present in the product of nitration by adding benzol thereto at the end of the nitrating operation.

It is, of course, known that picric acid is soluble in benzol. By adding benzol to the product of nitration, picric acid is carried into solution but the metallic bodies do not pass into solution. Then after the excess of benzol has been driven off, the residue containing a sufficiency of benzol is allowed to crystallize, the crystals consist-

ing of a loosely linked compound of picric acid and benzol, and the uncrySTALLizable portion of the said residue (consisting of the impurities) is drained off. The benzol in the crystalline compound is easily separated from the picric acid leaving the latter pure.

The improvement consisting in the use of benzol in the manner and for the purpose just described, is applicable both in the known process which consists in treating mercury and nitric acid with benzol, and also in the known process which consists in first sulfonating phenol and treating this with sodium or potassium nitrate as will be hereinafter fully set forth.

Further improvements comprised within the present invention consist in carrying out the nitrating process at a low temperature, and in restraining nitration and driving off the nitro-benzol by means of steam. These improvements constitute an important part of the invention as by means of same the danger hitherto present at this stage of the process is entirely eliminated.

It is also an important feature of the invention that the materials used as agents for producing the picric acid may be wholly or partly recovered after use and may be used again as will be hereinafter described, thus making the process very economical.

To enable the invention to be clearly understood the same will be more specifically described with reference to a convenient form and arrangement of apparatus by the aid of which the process may be economically carried out.

The apparatus is illustrated diagrammatically in the accompanying drawing and comprises mainly, a mixing pan 1 fitted with internal movable beaters 2 and having a condenser tube 3, or other suitable condensing means, in connection therewith, capable of returning the condensate to the pan by a pipe 4 and, when required, carrying it away by a pipe 5 to a receiving vessel 6. The mixing pan 1 is also provided with a gage glass or other known means (not shown) whereby the level of the contents may be ascertained. Associated with the mixing pan is a crystallizing pan 7, and intermediate of the two pans is a condensing or distilling apparatus of any suitable form 8, such apparatus having a connection by a pipe 9.

with the mixing pan 1 and also by a pipe 10 with a storage tank 11. Means 12 and 13 for draining each pan are provided and a liquor tank 14 is arranged to receive the 5 drainage from the crystallizing pan 7. Each pan is jacketed, the jackets 15 and 16 having steam and water connections 17, 18, 19, 20, a connection being provided from the mixing pan 1, to the crystallizing pan 7 by 10 means of the pipes 21 to 25. The mixing pan and beaters may be made of acid proof iron but the crystallizing pan and connections 21 to 25 and condenser 8 attached thereto should be made of earthenware, 15 aluminium or tin.

At the commencement of the process the materials may, for example, be used in the following proportions viz:—

20 Mercury (metal) --- 4 parts (by weight)
Nitric acid (s. g. 1.42) --- 100 parts (by weight)
Benzol (rectified) --- 32 parts (by weight)

The mercury is first dissolved in about 5 parts of the nitric acid, the solution is heated 25 preferably to boiling point and added to the remainder of the nitric acid in the mixing pan 1 through the inlet 26 and mixed, the benzol being then added in a slow stream over about three hours, or alternatively it 30 may be added in three separate portions during this period.

During the period of reaction the mixture is kept agitated by the beaters 2 and as the temperature has a tendency to fall during 35 the process, the pan 1 is heated by warm water in the jacket 15 to maintain the temperature of the mixture at approximately 35° C. The purpose of this low temperature is to produce largely, during the reaction, di- 40 nitrophenol in the first instance which later on, when the temperature is raised, is converted into tri-nitrophenol. The temperature should not however, exceed 40° C., since at a higher temperature than this a basic 45 mercuric picrate is liable to form, the yield of picric acid being thereby reduced. At a higher temperature than 40° C. picric acid would be formed, but since the reaction process extends over a period of 8 to 10 hours

50 if the higher temperature is maintained, the picric acid formed will be largely split up into oxalic acid and various other bodies. By carrying out the reaction during nitration at the comparatively low temperature 55 specified the formation of basic mercuric picrate is obviated and consequently the danger of explosion at this stage is eliminated. A thermometer of suitable type is inserted through an opening or plug in the 60 top 27 of the pan to ascertain the temperature.

After a period of about ten hours has been allowed for the reaction to take place—during which the nitro-benzol and nitric acid 65 which volatilize are collected through the

condenser tube 3, condensed and returned by the tube 4 to the pan—the temperature of the liquid is raised to boiling point and maintained thereat for a period of about one hour. The nitro-benzol and nitric acid driven off during ebullition is collected through the condenser tube 3 and directed by the pipe 5 into the receiving vessel 6 and reserved for further use as will be explained later herein.

A jet of steam (preferably dry) is now blown through the liquid conveniently by a pipe 28 (or the spindle 29 of the beaters may be hollow to admit the steam) during which operation also the volatilized nitro-benzol is collected through the condenser tube 3 and carried off to the receiving vessel 6 just referred to. Preferably the steam is blown through the liquid at or about the same time that the temperature of the latter is raised as aforesaid but it may be introduced at an earlier or later stage if desired.

The use of steam forms an important part of this invention seeing that it is one of the contributory features to the elimination of danger from the process. By introducing steam into the mass at that stage in the nitration process when it is desirable that further nitration should be prevented, the extreme oxidation of the phenolic bodies into oxalic acid and the like which will take place unless the strong nitrating agent is diluted, is obviated. The steam therefore constitutes a diluting or restraining agent and at the same time carries off the nitro-benzol and any mono-nitro-phenol which may be volatile at the temperature employed, thus facilitating the purification and final crystallization of the picric acid.

When practically all the nitro-benzol has 105 been removed from the mixture and collected in the manner described, the steam is shut off. Fresh benzol (about 60 parts) is then added to the mixing pan, and after the contents have been thoroughly mixed for 110 about fifteen minutes the mixture is allowed to settle; whereupon the benzol portion containing crude picric acid is tapped off at 21 and run into the crystallizing pan 7.

The crystallizing pan is then steam heated 115 by the jacket 16 whereby the benzol is volatilized and by passing through the condensing coil 8 is distilled back through the pipe 9 into the mixing pan 1.

The contents of this pan 1 are again thoroughly mixed, allowed to settle, and the benzol again tapped off at 22 and run into the crystallizing pan 7. The crystallizing pan is then heated to drive off about half the benzol which is distilled by the condenser 8 and carried by the pipe 10 to the storage tank 11 and reserved for further use, and then the said pan is water cooled by the jacket 16 to cause crystallization of the contents. The mother liquor is drained off from 130

the crystallizing pan by the connection 13 and collected in the liquor tank 14 the said liquor containing some picric acid, ortho-mononitrophenol, nitro-benzol and benzol.

5 About 30 parts of fresh benzol are now added to the contents of the crystallizing pan 7 by means of the inlet 7*, the pan is heated, to dissolve the contents after which it is cooled to cause crystallization. When 10 crystallization has taken place the liquor is drained off at 13 and collected in the liquor tank 14.

Samples of crystals (which contain combined benzol) are now taken from the crystallizing pan, and the benzol is dissipated with heat of say a water-bath. The residue 15 consisting of picric acid is tested for melting point, which, with two crystallizations as described, should be 122° C. sharp.

20 Upon the melting point being found correct the crystallizing pan is again heated by a gradually increasing temperature up to about 100° C., to drive off the last traces of the benzol, the remaining contents of the pan being pure picric acid. The crystallizing pan is fitted with an observation glass 30 which may be removed for sampling the crystals.

The remaining contents of the mixing pan 30 1 are now heated until all the nitric acid and moisture are driven off and collected by the condenser tube 3 into the receiving vessel 6; leaving practically dry mercury salt in the pan. It is preferable to carry out 35 this evaporation at a low temperature by means of a vacuum.

When starting a fresh batch, a portion of the nitric acid charge is added to the mercury salt and warmed in the mixing pan 1 40 until solution is effected, then the remainder of the nitric acid is added and the process is continued as before, no further mercury being required, although it may have to be renewed from time to time on account of 45 accumulating iron salts.

The time occupied by the complete process is approximately 24 hours although it may be less of course when one of the crystallizations is omitted.

50 The picric acid left in the mother liquor may, if desired, be recovered from this by prolonged crystallization and if the residual liquor is treated with a jet of dry steam, which removes the nitro-benzol and benzol, 55 the ortho-mononitro-phenol will be left in a condition suitable for dye manufacture.

This nitric acid and nitro-benzol collected in the receiving vessel 6 may be separated in any known manner and collected in tanks 60 31, 32 and the nitric acid may be revivified or concentrated and used again in this process.

The benzol distilled into the storage tank 11 may also be used again.

65 Therefore, in so far as the materials em-

ployed may, by condensing and collecting the nitric acid from the mixing pan 1, distilling and collecting or returning to the mixing pan the benzol from the crystallizing pan 7, and separating from the remaining 70 contents in the mixing pan the dry mercury salt, be recovered and used again the process may be said to be economical.

As the process is carried out in a closed apparatus and the temperature during the 75 process has a natural tendency to fall all danger is eliminated, in addition to which the necessity for personal attention is considerably reduced.

Obviously it will depend upon the quantity or level of the solution in the mixing pan as to which of the outlets 21, 22 or 23 is used for tapping off at each operation. A branch 3* on the condenser tube 3 may lead to a suitable acid tower so that any 85 nitrous fumes given off may be oxidized and returned to the mixing pan 1.

Hitherto, there has been attendant with the process of producing picric acid which consists in first sulfonating phenol and 90 then treating this with sodium or potassium nitrate in such a manner that picric acid is formed together with considerable quantities of sodium or potassium sulfate or acid-sulfate or mixture of same, great difficulty 95 in extracting the picric acid; also considerable waste of same in the process of washing as usually carried out. These disadvantages have been so pronounced as to retard somewhat the development of processes of 100 making picric acid with nitrates of the alkalis.

By the use of benzol according to the present invention the aforesaid disadvantages are overcome. This is achieved by 105 treating the mixture of picric acid and sulfate, or the acid-sulfate of the alkalis, according to the process used, with benzol.

By treating the aforesaid mixture with benzol in a suitable apparatus in the presence of mineral acid, (such as sulfuric acid) and with or without added water at a suitable temperature above the freezing point of benzol, the picric acid together with any organic by-products passes into solution. 110

According to an example of the process, 100 parts of phenol may be heated with say 1000 parts of concentrated sulfuric acid for say two hours at a temperature of 170° C. this producing phenol-di-sulfonic acid. 115

To this 96 parts of dry powdered Chile salt-peter are added and heated at 140° C. producing nitro-phenol-di-sulfonic acid. This is diluted with 320 parts of water and heated to 80°-90° C. with 244 parts of Chile salt-peter, the temperature being allowed to reach 140° C. in about two hours. 120

In carrying out this process an apparatus of the kind already described may be used for the nitration of the sulfonated phenol 130

and the extraction of the picric acid. After the mixture has cooled to somewhere about 40° C., approximately 400 parts of benzol are added thereto and the solution of picric acid in benzol is tapped off and run into the crystallization pan and then treated in the manner previously mentioned, the benzol being driven off and condensed and returned to the mixing pan or collected in 10 the storage tank leaving the picric acid in the pan 7.

If other organic bodies are present at this stage a suitable quantity of benzol is left in the picric acid in the crystallizing pan. 15 This pan is cooled and the contents allowed to crystallize in the form of a loose compound of picric acid and benzol from which is subsequently drained the uncombined benzol together with such impurities as may be 20 present. The picric acid may be recrystallized from further benzol if desired.

In the process just described, instead of the sodium nitrate the calculated quantity of potassium nitrate may be used.

25 The invention is not to be confined to the herein-mentioned quantities and details as these are given only as examples and may be varied if found necessary or desirable.

In the apparatus employed instead of tapping into solution off from the mixing pan 30 it may be separated by decantation or siphoning and the invention is not to be restricted to the precise construction and arrangement of the apparatus shown and described as the said apparatus may be modified without departing from its general character and principle of operation.

What I claim then is:—

1. In the process of producing picric acid wherein mercury and nitric acid are treated 40 with benzol, carrying out the reaction during nitration at a low temperature of approximately 35° C. for the purpose described.

2. In the process of producing picric acid wherein mercury and nitric acid are treated 45 with benzol, restraining nitration and oxidation and driving off the nitro-benzol by means of steam substantially as and for the purpose herein described.

In testimony whereof I have signed my 50 name to this specification in the presence of two subscribing witnesses.

DAVID BAIRD MACDONALD.
